ONE-PIECE FIBERBOARD SHIPPING CONTAINER

Samuel P. Belsinger, Atlanta, Ga., assignor to
Belsinger, Inc., Atlanta, Ga., a corporation of
Georgia

Application December 15, 1949, Serial No. 133,038

1 Claim. (Cl. 229—16)

1

This invention relates to a container construction which is of particular value for shipment of piece goods such as woven or knitted cloth, and bulky package goods of low density.

A feature of the invention is the provision of a container and a blank therefor, in which the blank material of fiber board, corrugated board and the like has areas for providing front, side and rear walls, each with top and bottom flaps, which can be sold and shipped as such, or as a sub-assembly or tubular form or as a further partial assembly in which the bottom wall flaps and certain of the top flaps have been located and connected; and in which the assembled container is of depth capable of holding piece goods in the bolt and of receiving such bolts through an opening provided in such further partial assembly by a front door structure formed in the original blank and having connected therewith top wall flaps which upon closing of the door structure serve to stiffen the container during transit; and in which the assembled container can be opened by releasing said door structure, whereafter the container can be employed for accessibility storing the contents while the closed door structure serves to exclude dirt.

Another feature of the invention is the provision of a container and a blank therefor of fiber board, corrugated board and like stiffly flexible materials herein referred to as "fiber board"; wherewith the same may be cut and shipped in the flat or in a sub-assembly condition, and set up and its parts connected ready to receive the contents, with side, bottom and rear walls connected with one another and with parts of the top and front walls likewise connected, while other parts of the top and front walls can swing about hinge lines provided by the blank material itself whereby to permit easy loading and unloading.

A further feature is the provision of such a container and the blank therefor, in which the swingable parts of the top and front walls are connected together at hinge lines provided by the blank material itself, and when in closed positions come into alignment and abutment with other parts of the container assembly whereby the contents can be sealed off by closing tapes extending in planes across abutment lines and extending around abutment corners.

A further feature is the provision of such a container and a blank therefor, having a total height in excess of the reach of the normal packer (e. g. greater than 28 inches) and so conformed and arranged that the packer has reach-

2

ing access to the inner bottom wall for aligning and avoiding distortion of the contents at the bottom.

With these and other features as objects in view, as will appear in the course of the following description and claim, illustrative forms of practicing the invention are shown on the accompanying drawings, in which:

Figure 1 is a lay-out diagram of a blank for the construction of a first form of the container.

Figure 2 is a perspective view showing a container formed from the blank of Figure 1, in partly assembled condition and ready for packing or unpacking.

Figure 3 is a perspective view of the same container in fully assembled or closed position, ready for shipment.

Figure 4 is a lay-out diagram of a blank for a modified form of container.

Figure 5 shows a partially assembled container as set up from the blank of Figure 4, ready for unloading.

Figure 6 is a perspective view of the same container, in fully assembled and closed condition, ready for shipment.

Figure 7 is a perspective view indicating the collapsing of a container sub-assembly at the factory for flat shipment.

The blank of Figure 1 is of rectangular outline, and it will be noted that there is essentially no wastage of material. The illustrated containers have two wide walls and two narrow walls so that they are oblong in horizontal cross-section, wherewith the wider walls are herein designated as front and rear panels, and the narrower walls are designated as side panels, but it will be understood that this is intended as illustrative and that the container may have various horizontal cross-sections as best adapted for the goods to be packed.

The blank of Figure 1 has the successive arrangement of a side wall 10, a rear wall 11, a side wall 12, and a front wall comprised of two sub-panels 13 and 130, separated by a weakening line illustrated as a horizontal cut 14. These wall panels are separated successively from one another at fold lines 15 which will later provide vertical hinges or edges in the assembly. Correspondingly, the wall panels are connected across upper fold lines 16 with corresponding top flaps 20, 21, 22, 23, these flaps being separated successively from one another by cut lines or gashes 24. Likewise, each of the panels is connected across a lower fold line 25 with a corresponding bottom flap 30, 31, 32, 33; these bot-

tom flaps being successively separated from one another by the cut lines or gashes 34. The lines 15, 16, 25 are fold lines in the assembly of the container; and it is preferred to assure folding at predetermined locations by scoring the blank along these lines. It will be noted that the blank can be formed from fiber board, corrugated board, etc., by the usual factory operations of punching with cutting and scoring rules, or by the use of cutting and scoring rollers, or by use of band or other saws for cutting the edges and gashes, or by various combinations of these and other operations known to box manufacturers.

The blank of Figure 1 is preferably partly formed at the factory, by employing a fabric tape 40 to join the free edge of the front sub-panel 13 to the corresponding part of the free edge of the side panel 10, therewith folding the various panels about their hinge lines 15 and forming a prism which can then be crushed down (Figure 7) by pressure in the direction of the arrows, to form a flattened structure of double the thickness of the original material. Thus, the boxes can be sold and shipped in flat condition from the factory to the packer.

When the packer desires to employ the container, he continues with a partial assembly by opening the flattened illustrative container to rectangular tubular form and folding the bottom flaps 30, 32 inward and then folding the bottom flaps 31, 33 inward so that two layers of flaps are formed, with use of a cemented tape 41 over the abutting edges on the flaps 31, 33, and continuing around the horizontal edges and onto the side walls 10, 12. Tapes 42 may also be employed over these horizontal edges, for connecting the flaps 31, 33 with the side walls 10, 12 and sealing these edges. The top flaps 20, 22 are similarly folded inward and then the flap 21 is brought over them (Figure 2) and the short tapes 43 are applied over the edges of flap 21 and side walls 10 to secure the parts and seal the container along these lines. It will be noted that the structure can be sold and delivered in this form.

In this condition as shown in Figure 2, the top panel portion 130 of the front wall can be swung to the side, with its flap 23, about the vertical hinge provided in the blank material by the corresponding fold line 15; and the packer thus has access to the interior of the container above the cut edges of the lower panel 13 of the front wall, provided by the cut line or gash 14 of the blank of Fig. 1. As indicated above, the edge provided by the cut line 14 can be less than 28 inches from the floor, when the box is standing in the position shown in Figure 2, even for a container having a total height exceeding 60 inches. For example, with a 50 inch container, the line 14 may be placed 20 inches from the floor or bench, whereby even a short woman packer can deposit articles with care upon the bottom wall of the box. This is of great value, as it avoids crumpling of piece goods at the bottom ends of the bolts.

The lading is built up within the container, in the case of packing folded textile goods or individually-packaged articles, with a sliding of the last row or rows of articles into position closely beneath the top wall provided by the flaps 20, 22. When the loading has been completed, the upper panel 130 of the front wall is swung into its closed position, therewith its flap 23 comes to overlie the flaps 22, 20, and presents its free edge into abutment with the free edge of the top flap 21. Also, the lower edge of the

top panel 130 comes into alignment with the top edge of the lower panel 13 so that the panels 13, 130 are co-planar. In this position of parts, a cementing tape 44 can be pasted over the adjacent edges of the panels 13, 130 and around the upright edges of the box onto the side walls 10, 12. Also, a tape 45 can be cemented over the vertical edge provided by the upper panel 130 and the side wall 10; tapes 46 can be cemented at the top horizontal edges to join the flap 23 with the side walls 10, 12; and a tape 47 can be cemented over the co-planar surfaces adjacent the abutment of the top flaps 21, 23, carrying this tape 47 down onto the side walls 10, 12. Thus, the completed package as shown in Figure 3 has its edges joined and sealed by tapes for providing strength and preventing loss of contents, penetration of dirt, or pilfering.

In the modified form shown in Figures 4 to 6, the rear blank has in succession a side wall panel 50, a rear panel 51, a side wall panel 52 and a front wall provided by a main panel portion 53, and an upper sub-panel portion 253, 153; these panels being successively connected across fold lines 55. Fold lines 56 define connections of these vertical wall panels with corresponding top flaps 60, 61, 62, 63 and 163; the flaps 63 and 163 together providing a top flap structure for the front wall. In corresponding fashion, fold lines 65 provide connection of the vertical wall panels with the bottom flaps 70, 71, 72 and 73. The top flaps are separated successively by the gashes 64, and the lower flaps by the gashes 74. The individual flaps 63, 163 are separated from one another by a weakening line 166 shown as provided by longitudinally aligned slits cut through the material, this line of slits being continued onto the front wall to provide for separation of the front wall sub-panels 253, 153, in conjunction with a similar weakening line 167 extending horizontally on the front wall to provide separation of sub-panels 253, 153 from sub-panel 53. Thus, the blank of Figure 4 can be manufactured as described above for the blank of Figure 1, partly assembled by use of a vertical edge tape 80 (Figure 5) connecting the front panel 53 with the side panel 50 corresponding to the employment of tape 40 in the form of Figures 1 to 3, and this tubular structure then crushed down as indicated by Figure 7 for sale and shipping in the flat. By this employment of weakening lines 166, 167, it will be noted that the parts providing the wall portions 50, 51, 52, 53, with their corresponding flaps, remain integrally joined with the portions comprising the panels 153, 253 and flaps 63, 163.

At the packer's plant, the blank is set up in essentially the same manner as described for structures Figures 1 to 3, wherewith a partially assembled container as in Figure 5 is produced. The weakening lines 166, 167 are broken through and the upper doors provided by the panels 153, 253 are swung sidewise about their vertical hinges provided respectively by the upper part of the tape 80 and by a fold line 55, carrying with them their top flaps 63, 163, for example to the positions shown in Figure 5, in which packing can be accomplished in the manner described for the form of Figures 1 to 3. Here, also, the container can be sold and delivered in this state of assembly. When packing is completed, the door panels 153, 253 with their flaps are swung to closed position and the sealing tape 84 (corresponding to tape 44) applied across the abutment edges of the front wall panels 53, 153, 253,

with the ends of the tape extending onto the side walls 52, 50. Tape 85 is cemented across the abutment edges where the panels 153, 253 join, with this tape 85 being extended also over the top of the container to connect and seal the top flaps 63, 163 and being carried past their abutment with the top flap 61. The tape 86 (corresponding to tape 47) is cemented over the abutment of the flaps 63, 163 with the flap 61, and has its ends carried over the horizontal edges and onto the side walls 50, 52. Tapes 46 can be used. Thus, this form of construction likewise provides a strong and tightly sealed box, as shown in Figure 6, with smooth external walls having the various lines of abutment and edges of juncture of the door structure and flaps connected and sealed by cemented tapes.

Each of these packages, upon arrival at the retail store, for example, can be easily opened by splitting the tapes 44, 45, 46 and 47 for the form of Figures 1 to 3; or the tapes 84, 85, 86, 46 for the form of Figures 4 to 6. This frees the doors so that they may be opened with their flaps to the positions shown in Figures 2 and 5, respectively, and part or all of the merchandise can be removed. It will be noted that the containers form excellent storage boxes at the store, as the door structures can be swung closed again without trouble, and can be held in closed position by a short piece of tape, thereby preventing the entry of dust or dirt to the goods remaining in the container.

It is obvious that the invention is not limited to the illustrative forms of construction, but that it may be employed in many ways within the scope of the appended claim.

I claim:

A tall upright container formed from a one-piece fiber board rectangular blank cut and scored so that when assembled a shipping container is provided comprising a rear panel, a front panel and side panels, each of said panels having an integral flap forming a bottom end closure on which said container normally rests

and is packed, said panels being dimensioned so as to provide a packing space of greater depth than the normal reach of a packer, said side panels at their upper ends having integral flaps 5 folded into a common plane and said rear panel at its upper end having an integral flap folded down onto the side panel flaps and secured to the side walls by taping, said front panel being divided horizontally approximately midway its 10 height to provide upper and lower sub-panels, said lower sub-panel being rigidly connected to the side panels to define with the side and rear panels a packing space beneath the upper terminus of said lower panel which has a depth not exceeding the normal reach of a packer, said upper sub-panel being initially connected to one of said side panels so as to swing outwardly and form an access opening for packing the container, said upper sub-panel having an integral flap dimensioned to overlie the upper side panel flaps, and 20 abut the free edge of the upper rear panel flap, said container being closed by swinging said upper sub-panel into the same plane as the lower sub-panel with its integral flap overlying said upper side panel flaps and with its free edge abutting the free edge of the upper rear wall flap and by taping said last named abutting edges, the adjacent edges of the upper and lower sub-panels, and the free side of the upper sub-panel to the adjacent side panel.

SAMUEL P. BELSINGER.
